UNITED STATES PATENT OFFICE.

DAVID HUARD, OF ASHLAND, WISCONSIN.

IMPROVEMENT IN LAST-BLOCK FASTENERS.

Specification forming part of Letters Patent No. **140,827**, dated July 15, 1873; application filed May 10, 1873.

To all whom it may concern:

Be it known that I, DAVID HUARD, of Ashland, in the county of Ashland and State of Wisconsin, have invented a new and Improved Last-Block Fastener, of which the following is a specification:

In the accompanying drawing, Figure 1 represents a vertical section of a shoemaker's last with my fastening attached, and Fig. 2 a plan view of the same.

Similar letters of reference indicate corresponding parts.

The object of my invention is to obviate the connection of last-blocks by nails, which gradually wear out the blocks and make them unfit for use, and substitute a cheap device which locks the blocks firmly to each other, and allows their rapid and easy separation. My invention consists of a clasp-like fastener, pivoted to the main block of the last, which closes over the other block in connection with pin-fastenings of the same.

In the drawing, A represents the main last; B, the block to be connected thereto; and C, the fastening-clasp. The last-block B is provided at its lower end with a pin, a, fitting into a recess of main block A, and at its upper end with a recess fitting over a sharp pin

or nail, b, of the main block A. A knob or button, d, of block B, at its upper part on the top of the same, serves, in connection with a similar button, d', of the top part of main block A, for locking the fastener C over the last-blocks. Fastener C is pivoted to button d' by means of a slotted recess, e', and has another slotted recess, e, open at one side to admit button d. The hook-like upturned end f of the fastener C serves as handle in turning the fastener over the blocks and sliding the same in recesses e e' to obtain their rigid closing over button d d'. The upper last-block B is thereby connected to block A in convenient manner, preventing the damage occasioned by nailing, and preserving them for a greater length of time in working order.

Having thus described my invention, I claim as new and desire to secure by Letters Patent—

The block-fastener C, having slotted recesses e e', pivoted by button d' to block A, substantially as set forth.

DAVID HUARD.
